UNITED STATES PATENT OFFICE.

CHARLES M. MAPES, OF NEW YORK, N. Y.

FASTENING FOR RAILWAY-TIES.

No. 884,941.

Specification of Letters Patent.

Patented April 14, 1908.

Application filed April 11, 1907. Serial No. 367,552.

To all whom it may concern:

Be it known that I, CHARLES M. MAPES, of New York city in the county of New York, and in the State of New York, have invented 5 a certain new and useful Improvement in Fastenings for Railway-Ties, and do hereby declare that the following is a full, clear, and exact description thereof, reference being had to the accompanying drawings, in which—

10 Figure 1 is a perspective view of a tie provided with my fastening for rails; Fig. 2 is a partial side view, partly in section, of one of the rail fastenings in Fig. 1; and Fig. 3 is a plan view of Fig. 2.

15 The object of my invention has been to provide a fastening for railway ties which shall be simple and cheap in construction and efficient in operation, and which shall protect the tie from being injured by the 20 flanges of wheels in case of derailment; and to such ends my invention consists in the fastening for railway ties hereinafter specified.

In carrying my invention into practice, I 25 provide a plate A which is adapted to be seated upon the tie B beneath the position which the rail C is to occupy, the plate being provided with flanges a that over-hang the sides of the tie, so that if a wheel escapes from 30 the rail, it will strike said flanges and will not cut into the tie. The plate is secured to the tie as by bolts D extending up through the tie and through holes in the plate. The rail C is seated upon the plate A and is held 35 in position by clips E, which over-lie the rail base on opposite sides, and which at their outer ends, relative to the rails, rest upon the plate A. The clips E are provided with downwardly bent portions e at their outer 40 ends, each of which portions is received in a slot a' formed in the plate A. The clips E are bolted down to the plate A by bolts F having their heads beneath the plate A, and having nuts f above the clips E, washers G 45 being preferably provided between the nuts

and the plate, the washers having their lower surfaces inclined to fit the clips. The bolts F pass through slots H, which are of sufficient size to permit the head of the bolt to pass, and then the shank of the bolt is 50 moved toward the rail into an extension I of the slot H. The bolt is thus quickly and easily engaged with the plate A without requiring to be passed through the plate from below. The slot H and the slot a' are separated by a 55 connecting piece K, thus making a much stronger construction than would be the case if the slots H and a' merged into each other. The connection K strengthens the side walls of the slots H and the extension I, and prevents their being bent upward under the strain of the bolts. The slot a' is made sufficiently larger than the downwardly bent portions e of the clips E, to permit sufficient adjustment of the clips to accommodate any 60 desired position of the rail.

I claim:—

A fastening for railway ties, comprising a plate adapted to be secured to the upper surface of the tie, and having flanges adapted to 70 over-lie the upper edges of the tie, clips adapted to bear upon the rail-base flanges, said clips having at their outer ends downwardly bent extensions, slots formed in said plate and adapted to receive said downwardly bent extensions, slots formed in said plate beneath an intermediate portion of said clips, said slots comprising a larger portion that is adapted to receive the head of a bolt, and a smaller extension that is adapted to receive only the shank of the bolt, said plate 75 having a connecting piece interposed between said slots to strengthen the walls of the latter slot, and of the extension.

In testimony that I claim the foregoing I 80 have hereunto set my hand.

CHARLES M. MAPES.
